FIG. 1 is a front perspective view of a new, original, and ornamental USB receptacle device design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a front perspective view of another new, original, and ornamental USB receptacle device design;

FIG. 10 is a rear perspective view of the USB receptacle device of FIG. 9;

FIG. 11 is a front elevation view of the USB receptacle device of FIG. 9;

FIG. 12 is a rear elevation view of the USB receptacle device of FIG. 9;

FIG. 13 is a left-side elevation view of the USB receptacle device of FIG. 9;

FIG. 14 is a right-side elevation view of the USB receptacle device of FIG. 9;

FIG. 15 is a top plan view of the USB receptacle device of FIG. 9;

FIG. 16 is a bottom plan view of the USB receptacle device of FIG. 9;

FIG. 17 is a front perspective view of another new, original, and ornamental USB receptacle device design;

FIG. 18 is a rear perspective view of the USB receptacle device of FIG. 17;

FIG. 19 is a front elevation view of the USB receptacle device of FIG. 17;

FIG. 20 is a rear elevation view of the USB receptacle device of FIG. 17;

FIG. 21 is a left-side elevation view of the USB receptacle device of FIG. 17;

FIG. 22 is a right-side elevation view of the USB receptacle device of FIG. 17;

(Continued)

FIG. 87 is a top plan view of the USB receptacle device of FIG. 81;
 FIG. 88 is a bottom plan view of the USB receptacle device of FIG. 81;
 FIG. 89 is a front perspective view of another new, original, and ornamental USB receptacle device design;
 FIG. 90 is a rear perspective view of the USB receptacle device of FIG. 89;
 FIG. 91 is a front elevation view of the USB receptacle device of FIG. 89;
 FIG. 92 is a rear elevation view of the USB receptacle device of FIG. 89;
 FIG. 93 is a left-side elevation view of the USB receptacle device of FIG. 89;
 FIG. 94 is a right-side elevation view of the USB receptacle device of FIG. 89;
 FIG. 95 is a top plan view of the USB receptacle device of FIG. 89; and,
 FIG. 96 is a bottom plan view of the USB receptacle device of FIG. 89.
